BRAKE SHOE

Robert E. Pogue, Orange, N. J., assignor to
American Brake Shoe Company, a corporation
of Delaware

Application May 8, 1943, Serial No. 486,141

15 Claims. (Cl. 188—258)

This application is in part a continuation of my copending application Serial No. 481,536, filed April 2, 1943, now abandoned.

This invention relates to brake shoes of the kind which have ductile metal reenforcements embedded in the cast bodies at the backs thereof.

The ductile metal reenforce that is embedded in the cast body of a brake shoe is intended to be effective to resist fracture of the cast body and, in the event of fracture of the body, to prevent separation of the fractured parts of the body one from the other and the reenforce and also to resist straightening of the arcuate shoe when the wearing face thereof is heated in the course of use of the shoe and to enable these and kindred desiderata to be realized in a novel and effective manner is the primary object of the present invention.

It has been observed that if a ductile metal reenforce, commonly called a steel back, that is embedded in at the back of a cast body of a brake shoe is provided with openings into which the body metal may flow during casting of the body and such openings are sized so as not to impair the innate strength of the reenforce back and the body is fractured in the course of use of the shoe, the edge portions of the openings that are presented to the portions of the metal body therein may be of such restricted area that any relative movement which may arise between such portions of the body metal and such edges of the openings, which may accrue by reason of fracture of the body metal and the vibration to which the shoe is subjected in the use thereof, will effect comparatively rapid wear of the edges of the openings particularly toward the adjacent end of the shoe. This may result in such enlargement of the openings in the ductile metal reenforce plate that the desired anchoring of the body metal therein can no longer be realized with the result that a fractured part of the body metal may separate from reenforce or plate and fall away from the shoe. It is, therefore, an important object of this invention to so locate, size and relate openings in a ductile metal reenforce for a brake shoe that the combined area of the edge portions of such openings that is presented to the body metal therein will be such as to effectively resist wearing away of such edge portions in the event the body is fractured and when the shoe is subjected to vibration in the course of use thereof.

Moreover, it has been found to be advantageous to reenforce a ductile metal reenforcement or back of the aforesaid character longitudinally

thereof by affording a reenforcing panel on the reenforcement or plate substantially medially between the side marginal edges thereof. In those instances where such a panel has projected above the upper surface of the plate it has been found that objectionable stresses may sometimes be set up, particularly in the event of fracture of the body metal, and these may result in such fracture of the plate or back that it is prevented from performing its intended function. Hence, it is another important object of this invention to afford a unitary reenforcing panel on a ductile metal reenforcement or reenforce plate of the aforesaid character and yet avoid setting up such stresses and strains that the reenforcement might be fractured in course of the use of a shoe in which it is included, and objects ancillary to the foregoing are to afford a reenforcing panel on a reenforce or back of the aforesaid character substantially medially between the side marginal edges of the back and on the lower or inner surface thereof; to roll such a reenforcing panel on a reenforce plate; and to recess the upper surface of the plate so as to thereby facilitate rolling such a reenforcing panel thereon.

While the primary stresses and strains to which the brake shoe is subjected in the course of use thereof are impressed on the shoe longitudinally, which makes it important to prevent longitudinal separation between a ductile metal reenforce or steel back and the cast body metal of the shoe longitudinally thereof, it is also necessary to insure against separation of portions of the body metal one from the other and the back, in the event of fracture of the body metal, transversely of the shoe and back and to enable this to be realized in a novel and effective manner is yet another important object of this invention; and objects ancillary to the foregoing are to include depending flanges along the side marginal edges of a reenforce plate or back of the aforesaid character which will be effective to resist transverse separation of portions of the body metal one from the other and from the reenforce plate or back in the event of fracture of the body metal; to afford openings in a reenforce plate or back of the aforesaid character in such locations that the openings will be effective to resist both longitudinal and transverse separation of portions of the body metal one from the other and from the reenforce plate in the event of fracture of the body metal; and to so relate depending flanges along the side marginal edges of a reenforce plate or back of the aforesaid character and openings afforded in the back that separation of portions

of the body metal one from the other and from the reenforce plate or back will be effectively resisted in the event of a fracture of the body metal in the course of the use of the shoe.

It is desirable that a reenforce plate or back of the character to which this invention pertains be effectively reenforced and while a reenforcing panel, such as that referred to hereinabove, enables such reenforcement to be afforded, I have found that the provision of depending side flanges, such as those described hereinabove, also effectively reenforce such a plate, particularly when such a panel and such reenforcing flanges are related one to another in substantially parallel but spaced apart relation and to so relate such a panel and such flanges is another object of this invention and another object, ancillary to the foregoing is to extend the flanges beyond the adjacent face of the plate for a distance different from the extent of the panel beyond such face whereby the free edges of the flanges, the face of the panel and the adjacent face of the plate are disposed in different and spaced apart planes for I have found that so to do affords appreciable reenforcement for the plate.

Moreover, by relating a reenforcing panel and side flanges one to the other in the just described manner, I afford channels therebetween in which portions of the body may anchor and thereby an effective interconnection is afforded between the reenforcing plate and the body and so to do is yet another object of this invention; and another object, related to the foregoing, is to afford openings in the back or plate in alignment with channels formed as aforesaid so that portions of the body may extend into such openings so as to thereby augment the aforesaid effective interconnection between the body and reenforce back.

A brake shoe customarily includes an attaching lug on the back substantially midway between the ends thereof and such an attaching lug usually embodies a strap of ductile metal that is formed to afford a keyway and it is customary during casting of the shoe to cause portions of the body metal to flow about at least portions of such a strap so as to, among other things, prevent the ductile metal or steel strap from coming into contact with the head into which the attaching lug is fitted so as to thereby avoid objectionable wearing of the head. It is, of course, essential that the strap that is formed to afford a keyway in the attaching lug to be firmly united with the ductile metal reenforce or steel back, and one way in which this has been accomplished heretofore has been to pass the free end portions of such a strap through openings in the reenforce plate or back and to clench these end portions against the underside of the back so as to thereby retain shoulders formed on the strap in engagement with the upper surface of the reenforce plate or back. Heretofore, however, arrangements of this character have been of such nature that some difficulty was sometimes encountered in causing the body metal to flow about the strap in the casting operation and it is therefore still another important object of this invention to so attach a strap of the aforesaid character to a reenforce plate or back of the aforesaid character that a firm union between the strap and back will be realized and yet to insure that body metal will flow about the strap in the course of the casting operation, and another object ancillary to the foregoing is to afford relatively enlarged openings in the ductile

metal reenforce or steel back adjacent to the openings through which portions of the attaching strap are passed and through which relatively enlarged openings body metal may flow in the course of casting of the shoe so that the body metal provided about the attaching strap will be anchored to the main portion of the body metal of the shoe through the relatively enlarged openings in the back which are located adjacent to the attaching strap.

Other and further objects of the present invention will be apparent from the following description and claims and are illustrated in the accompanying drawings which, by way of illustration, show preferred embodiments and the principle thereof and what I now consider to be the best mode in which I have contemplated applying that principle. Other embodiments of the invention embodying the same or equivalent principles may be used and structural changes may be made as desired by those skilled in the art without departing from the present invention and the purview of the appended claims.

In the drawings:

Fig. 1 is a side view, partly in elevation and partly in section, of a brake shoe embodying my invention;

Fig. 2 is a plan view of the ductile metal reenforce that is embedded in the back of the shoe shown in Fig. 1, the body metal that is to be cast about such a reenforce being shown in broken lines;

Fig. 3 is a longitudinal sectional view taken substantially on the line 3—3 on Fig. 2;

Fig. 4 is a fragmentary plan view of the medial portion of the reenforce with the attaching lug strap shown in Fig. 2 removed;

Figs. 5 and 6 are transverse sectional views taken substantially and respectively on the lines 5—5 and 6—6 on Fig. 1;

Figs. 7 and 8 are views respectively similar to Figs. 2 and 4 but showing a modified form of my invention; and

Figs. 9 and 10 are sectional views taken substantially and respectively on the lines 9—9 and 10—10 on Fig. 7.

In the form of my invention shown in Figs. 1 to 6, inclusive, of the accompanying drawings, the shoe there illustrated includes a body 7 preferably of cast iron, and, in accordance with well understood practices in the art, chilled sections are afforded in the body particularly at the ends and adjacent to the wearing face thereof and, if desired, an expanded metal or other reenforce (not shown) may be included in the body 7. A ductile metal reenforce 8, commonly referred to as a steel back, is embedded in the back of the shoe at the face thereof opposite the wearing face, and this back is desirably so sized as to terminate in spaced relation with opposite ends of the body 7 of the same shoe, the end portions of the back or reenforce plate 8 desirably being arranged beneath the end stops 9 provided on the back of the shoe at the ends thereof as is customary in the art.

My invention primarily has to do with the ductile metal reenforce or steel back as 8 and desirably such a back is hot-rolled to include a reenforcing panel 10, that is extended longitudinally substantially midway between the side marginal edges thereof. Flanges 11 and 12 are also rolled along the side marginal edges of the back. The reenforcing panel 10 and flanges 11 and 12 are formed on the lower or inner side of the back 8 and the upper face of the back is desirably flat

transversely thereacross, the back being curved longitudinally thereof, as best shown in Fig. 1, so as to be complementary to the curved wearing face 13 of the shoe.

An attaching lug 14 is provided on the back of the shoe substantially medially between opposite ends thereof and this lug includes a strap 15 that is bent to include two upwardly or vertically extending and spaced apart arms and an interconnecting section that extends between the upper ends of these arms in spaced relation with the upper surface of the back 8 when the strap 15 is mounted on the back, whereby the strap, in cooperation with the adjacent portion of the back, defines a keyway through which a key may be passed to secure the shoe to the head customarily afforded on railway equipment to receive the shoe. End portions or tongues 16 and 17 are provided at the lower ends of the vertically extending arms of the strap 15 and these end portions are desirably narrower than the vertically extending arms so that shoulders as 18, Fig. 3, are provided at the lower ends of the vertically extending arms of the strap.

Slots as 19 and 20 are formed in the back or reenforce plate 8 substantially midway between the ends thereof and in such locations that adjacent edges of the slots are respectively aligned with opposite side marginal edges of the reenforcing panel 10, and relatively enlarged openings 21 and 22 are formed in the back respectively between the reenforcing panel 10 and the depending flanges 11 and 12 and in such locations that the slots 19 and 20 respectively open thereto. When the strap 15 is to be attached to the back 8 the end portions or tongues 16 and 17 thereof are respectively passed through the slots 19 and 20 and the shoulders 18 are rested on the top of the back 8 adjacent to these slots. Then, as best shown in Fig. 6, the tongues 16 and 17 are folded toward each other and into engagement with the lower surface of the reenforcing panel 10 so as to thereby clench the strap 15 to the back or reenforce plate 8.

As has been explained hereinabove, it is desirable that openings be provided in a back as 8, into which the body metal may flow during casting of a shoe in which the back is to be included, and that these openings are to be related one to the other in such a way as to insure against excessive wear of the edges of these openings in the event of fracture of the body metal and when the shoe is subjected to vibration in the course of use thereof. To this end openings 23 and 24 are provided in the back 8 adjacent to the ends thereof and between the depending side flange 11 and the adjacent edge of the reenforcing panel 10, these openings desirably underlying at least part of the end stops as 9 in the finished shoe. Similarly arranged and located openings 25 and 26 are provided in the back 8 between the depending side flange 12 and the adjacent side edge of the reenforcing panel 10.

Additionally, at least two openings as 27 and 28 are formed in the back 8 between the depending side flange 11 and the adjacent edge of the reenforcing panel 10 and also between the openings 21 and 23. Desirably the openings as 27 and 28 are located on each side of a position substantially midway between the openings 21 and 23 for it has been found that openings so located, in cooperation with a side flange as 11, effectively resist separation of portions of the body metal one from the other and from the back as 8 in the event of fracture of the shoe. Another pair 75

of openings 29 and 30 are formed in the back 8 between the side flange 11 and the adjacent marginal edge of the panel 10 and these openings 29 and 30 are related to each other and the openings 21 and 24 in the same manner as that in which the openings 27 and 28 are related to each other and the openings 21 and 23. Another pair of openings 31 and 32 are formed in the back 8 between the depending side flange 12 and the adjacent margin of the reenforcing panel 10, and desirably these openings are respectively transversely aligned with the openings 27 and 28. Yet other openings 33 and 34 are formed in the back 8 between the side flange 12 and the adjacent side margin of the reenforcing panel 10 and desirably these openings are respectively transversely aligned with the openings 29 and 30.

A centering toe as T is usually provided at each end of a shoe on the back thereof to extend inwardly from the adjacent end of the shoe medially between the side edges thereof, and it has been found to be advantageous to effectively anchor such toes to the body metal 1. To this end openings 35 and 36 are formed in the back 8 adjacent to the ends thereof and respectively between the openings as 23 and 25 and 24 and 26, the openings 35 and 36 being desirably elongated longitudinally of the back 8 so as to underlie substantially all of the toes as T, this having been found to be effective to reenforce end stops as 9.

A shoe such as that illustrated in the accompanying drawings is customarily cast in a suitable mold and prior to the time the molten iron is poured into the mold the back or reenforce plate as 8 with the strap as 15 attached thereto is fixed in the mold in the manner customary in the art as well as any expanded metal or other reenforce that is to be included in the cast body 7 of the shoe. Desirably, the back 8 and the strap 15 are coated with a suitable refractory material prior to the time they are introduced into the mold so as to prevent burning thereof by the molten metal when it is poured into the mold, and as the molten metal flows into the mold it flows through the various openings provided in the back, and in so far as openings as 27 and 28 are concerned, the body metal is confined therein so as to be cast flush with the upper surface of the back as 8. However, in the course of the casting operation the molten metal will flow out through the openings 21 and 22 to afford projections of body metal as 37 about the upwardly extending portions or arms of the strap as 15. Moreover, as best shown in Fig. 3, the molten metal will flow through openings as 26 (and 23, 24 and 25) to thereby reenforce the end stops 9, metal also flowing through the openings 35 and 36 to reenforce the centering toes as T.

By reason of the fact that the cast portions as 37 about the vertically extending portions of the strap as 15 are effectively anchored to the body metal of the shoe through openings as 21 and 22, these cast portions are retained in position about these portions of the strap in the course of use of the shoe and hence these cast portions perform their intended function throughout the use of the shoe. Furthermore, because the portions as 37 are extended over the upper face of the back about the edges of the openings 21 and 22, the medial part of the body metal is effectively anchored to the back and is prevented from separating from the back in the event of fracture of the body metal in the course of use of the shoe.

In this regard, however, the reenforcing panel

10, particularly in cooperation with the side flanges 11 and 12, effectively reenforces the back or reenforce plate as 8, especially longitudinally thereof and this, it has been found, mitigates against likelihood of fracture of the body metal in the course of use of the shoe. Should the metal body fracture, however, the portions thereof anchored in openings at 23, 27, 28, 21, 29, 30 and 24, in cooperation with an adjacent side flange as 11, resist separation of the fractured parts from the back and each other.

Yet further, the combined surface area of the edges of, and the relation among, openings as 21, 28, 27 and 23 and openings as 22, 32, 31 and 25, in cooperation with the area of the edge of an opening as 35, is such that there is such distribution of the vibratory effect, which arises in the event of fracture of the body metal and when the shoe is subjected to vibration in the course of use thereof, that the aforesaid edges of the openings do not so rapidly wear away that such enlargement of these openings accrues as might result in loss of function with the result that the fractured parts of the body metal are effectively held in position, this desirable result accruing particularly longitudinally of the shoe.

Furthermore, in the event of fracture of the body metal, the extension of portions thereof into openings as 21, 28, 27 and 23 insures against transverse separation of the fractured parts from the back and each other primarily because these openings are aligned with a channel defined between the adjacent edge of the panel as 10 and the adjacent flange as 11, the extension of the body metal into this channel affording a firm anchorage between the body metal and the back or reenforce plate.

Moreover, the extent of the flanges as 11 and 12 beyond the adjacent face of the plate back is greater than the extent of the reenforcing panel as 10 beyond such face and therefore the free edges of the flanges, the exposed face of the panel and the adjacent edge of the plate back lie in different and spaced planes. This has been found to effectively reenforce the plate back so as to insure that this back will serve its intended function in the brake shoe in which it is included.

All of the foregoing advantages of my invention are also realized in form thereof shown in Figs. 7 to 10, inclusive, in the accompanying drawings where a back or reenforce plate 8a is illustrated. Since the back 8a and the shoe in which it is included are like the back and shoe shown in Figs. 1 to 6, the same reference characters employed in Figs. 1 to 6 are applied to the corresponding elements in Figs. 7 to 10 except that the suffix "a" is added when these reference characters appear in Figs. 7 to 10. Moreover, the hereinabove set forth description of my invention with reference to Figs. 1 to 6 applies to the form of invention shown in Figs. 7 to 10 except insofar as certain features of the back or plate 8a, as now to be described, are concerned.

Thus the back 8a is hot rolled so as to be of substantially uniform thickness in cross section between the flanges 11a and 12a and to this end a channel or recess C is rolled into the upper surface of the back 8a. Therefore, the top of the back 8a, unlike the top of the back 8, is not flat transversely thereacross. However, as the channel C is rolled into the back 8a, a reinforcing panel 10a is formed on the underside of this back and this panel, like the panel 10, reinforces the back, particularly in cooperation with the flanges 11a and 12a. Moreover, the side edges of

the panel 10a are desirably beveled to be complementary to the beveled side walls of the channel C. Likewise, the exposed edges of the flanges 11a and 12a are tapered or inclined inwardly. The provision of the channel C and the tapering of the exposed edges of the flanges 11a and 12a as well as the beveling of the edges of the panel 10a facilitates the rolling of the back 8a. In all other respects the form of my invention shown in Figs. 7 to 10 corresponds to that shown in Figs. 1 to 6.

A ductile metal reenforce of the character hereinabove described enables the above set forth objects of this invention to be realized and while I have illustrated and expressly described selected embodiments of my invention, it is to be understood that these are capable of variation and modification and I therefore do not wish to be limited to the precise details set forth but desire to avail myself of such changes and alterations as fall within the purview of the following claims.

I claim:

1. A brake shoe having a body, a reenforce plate extended to the side edges of the body and anchored to the body at the back thereof, and a center attaching lug, said plate having flanges along opposite edges and extended beyond the inner face thereof and into the body at the sides of the body, said plate also having a reenforcing panel extended from end to end thereof and on the inner face thereof and disposed in spaced relation with said flanges and extended into the body, said flanges being extended into the body in an amount greater than the reinforcing panel to retain the body against transverse separation in the event of fracture of the body, said plate also having a continuous recess formed therein in alignment with said panel whereby said plate is of substantially uniform thickness between said flanges.

2. A brake shoe having a body, a reenforce plate extended to the side edges of the body and anchored to the body at the back thereof, and a center attaching lug, said plate having flanges along opposite edges that are extended beyond the inner face thereof and into the body at the sides of the body, said plate also having a reenforcing panel on the inner face and extended from end to end thereof and disposed in spaced relation with said flanges whereby continuous channels are defined between said panel and said flanges, said reinforcing panel being extended into the body, said flanges being extended into the body in an amount greater than the reinforcing panel to retain the body against transverse separation in the event of fracture of the body, and said plate having openings formed therein in alignment with said channels in which portions of the body are anchored.

3. A brake shoe having a body, a reenforce plate extended to the side edges of the body and anchored to the body at the back thereof, and a center attaching lug, said plate having flanges along opposite edges thereof and a reinforcing panel disposed between said flanges and extended from end to end of said back and into the body, the free edges of said flanges, the exposed face of said panel and the adjacent face of said plate being disposed in different and spaced apart planes to thereby effectively reenforce said plate, said plate having a continuous recess formed therein in alignment with said panel whereby said plate is of substantially uniform thickness between said flanges, said flanges be-

ing extended into said body at the sides thereof and in an amount greater than that in which the panel is extended into the body to thereby be effective to retain the body against transverse separation in the event of fracture of the body.

4. A brake shoe having a body, a reenforce plate anchored to the body at the back thereof, and a center attaching lug, said plate having a reenforcing panel on the inner face and substantially midway between opposite edges thereof, said plate having an opening therein substantially midway between other opposite edges thereof and on each side of said reenforcing panel, said attaching lug including a strap formed to provide a keyway and having tongues formed thereon, said tongues being passed through said openings and folded over into said panel to secure said strap to said plate, and said plate having other and relatively enlarged openings therein respectively disposed adjacent to the first named openings therein and through which portions of the body disposed about said strap are connected to the portion of the body of the shoe below said plate.

5. A brake shoe having a body, a reenforce plate anchored to the body at the back thereof, and a center attaching lug, said plate having a reenforcing panel on the inner face and substantially midway between opposite edges thereof, said plate having an opening therein substantially midway between other opposite edges thereof and on each side of said reenforcing panel, said attaching lug including a strap formed to provide a keyway and having tongues formed thereon, said tongues being passed through said openings and folded over onto said panel to secure said strap to said plate, said plate having other openings therein respectively disposed to open into the first named openings whereby portions of the body extended through the first named openings and about adjacent portions of said strap are anchored to the portion of the body of the shoe below said plate.

6. A brake shoe having a body, a reenforce plate anchored to the body at the back thereof, and a center attaching lug, said plate having flanges along opposite edges and extended beyond the inner face thereof and also having a reenforcing panel on the inner face thereof disposed in spaced relation with said flanges whereby channels are defined between said panel and said flanges, said plate having an opening therein substantially midway between other opposite edges thereof and on each side of said panel and inwardly of the adjacent flange, said attaching lug including a strap formed to provide a keyway and having tongues formed thereon, said tongues being passed through said openings and folded over onto said panel to secure said strap to said plate, and said plate having other and relatively enlarged openings therein respectively disposed adjacent to the first named openings and inwardly of the adjacent flange and through which portions of the body are extended to be disposed about adjacent portions of said strap.

7. A brake shoe having a body, a reenforce plate anchored to the body at the back thereof, and a center attaching lug, said plate having flanges along opposite edges and extended beyond the inner face thereof and also having a reenforcing panel on the inner face thereof disposed in spaced relation with said flanges whereby channels are defined between said panel and said flanges, said plate having openings formed therein substantially midway between other op-

posite edges thereof and respectively aligned with said channels and including portions of restricted size, said attaching lug including a strap formed to provide a keyway and having tongues thereon that are respectively passed through the portions of restricted size of said openings and which are then folded over onto said panel to secure said strap to said plate, portions of said body being extended through said openings and being disposed about adjacent portions of said strap.

8. A brake shoe having a body, a reenforce plate anchored to the body at the back thereof, and a center attaching lug, said plate having flanges along opposite edges and extended beyond the inner face thereof and also having a reenforcing panel on the inner face thereof disposed in spaced relation with said flanges whereby channels are defined between said panel and said flanges, said plate having openings formed therein substantially midway between the opposite edges thereof and respectively aligned with said channels and including portions of restricted size, said attaching lug including a strap formed to provide a keyway and having tongues thereon that are respectively passed through the portions of restricted size of said openings and which are then folded over onto said panel to secure said strap to said plate, portions of said body being extended through said openings and being disposed about adjacent portions of said strap, said plate having other openings formed therein adjacent to said other opposite edges thereof and respectively aligned with said channels and into which the body is extended to be anchored therein.

9. A brake shoe having a body, a reenforce plate anchored to the body at the back thereof, and a center attaching lug, said plate having flanges along opposite edges and extended beyond the inner face thereof and also having a reenforcing panel on the inner face thereof disposed in spaced relation with said flanges whereby channels are defined between said panel and said flanges, said plate having openings formed therein substantially midway between other opposite edges thereof and respectively aligned with said channels, said attaching lug including a strap formed to provide a keyway and having portions extended through said openings and folded onto said panel to secure said strap to said plate, and said plate having other openings formed therein adjacent to said other opposite edges thereof and respectively aligned with said channels and into which the body is extended to be anchored therein.

10. A brake shoe having a body, a reenforce plate anchored to the body at the back thereof, and a center attaching lug, said plate having flanges along opposite edges and extended beyond the inner face thereof and also having a reenforcing panel on the inner face thereof disposed in spaced relation with said flanges whereby channels are defined between said panel and said flanges, said plate having openings formed therein substantially midway between other opposite edges thereof and respectively aligned with said channels and including portions of restricted size, said attaching lug including a strap formed to provide a keyway and having tongues thereon that are respectively passed through the portions of restricted size of said openings and which are then folded over onto said panel to secure said strap to said plate, portions of said body being extended through said openings and being dis-

posed about adjacent portions of said strap, said plate having other openings formed therein adjacent to said other opposite edges thereof and respectively aligned with said channels and into which the body is extended to be anchored therein, and said plate having other openings formed therein in alignment with said channels and respectively disposed between the openings midway between said other opposite edges thereof and the openings adjacent to said other opposite edges thereof, the body being extended into such openings to be anchored therein.

11. A brake shoe having a body, a reenforce plate anchored to the body at the back thereof, and a center attaching lug, said plate having flanges along opposite edges and extended beyond the inner face thereof and also having a reenforcing panel on the inner face thereof disposed in spaced relation with said flanges whereby channels are defined between said panel and said flanges, said plate having openings formed therein substantially midway between other opposite edges thereof and respectively aligned with said channels, said attaching lug including a strap formed to provide a keyway and having portions extended through said openings and folded onto said panel to secure said strap to said plate, said plate having other openings formed therein adjacent to said other opposite edges thereof and respectively aligned with said channels and into which the body is extended to be anchored therein, and said plate having pairs of openings formed therein, each such pair of openings being aligned with one of said channels and being disposed between an opening located midway between said other opposite edges of the plate and an opening adjacent to one of said other opposite edges of the plate, the body being extended into such openings to be anchored therein.

12. A brake shoe having a body, an elongated reenforce plate anchored to the body at the back thereof, and a center attaching lug, said plate having flanges along the side edges and extended beyond the inner face thereof and also having a reenforcing panel on the inner face thereof disposed in spaced relation with said flanges whereby channels are defined between said panel and said flanges, said plate having openings formed therein substantially midway between the ends thereof and respectively aligned with said channels, said attaching lug including a strap formed to provide a keyway and having portions extended through said openings and folded onto said panel to secure said strap to said plate, said plate having other openings formed therein adjacent to the ends thereof and respectively aligned with said channels and into which the body is extended to be anchored therein, said plate having pairs of openings formed therein, each such pair

of openings being aligned with one of said channels and being disposed between an opening located midway between the ends of the plate and an opening adjacent to an end of the plate, the body being extended into such openings to be anchored therein, and said plate having longitudinally enlarged openings therein in alignment with said panel and adjacent to the ends thereof.

13. A reenforce plate for a brake shoe or the like embodying a concavo-convex configuration between opposite end edges thereof, flanges along other opposite edges of said plate that are extended beyond the concave face thereof, and a reenforcing panel extended between said end edges on the concave face of said plate and spaced inwardly from said flanges whereby channels are defined on the concave face of said plate intermediate said panel and said flanges, the free edges of said flanges being disposed beyond the face of said panel whereby said flanges serve to retain the body of a brake shoe or the like in which the reenforce plate is incorporated against separation in the event of fracture of said body.

14. A reenforce plate for a brake shoe or the like embodying a concavo-convex configuration between opposite end edges thereof, flanges along other opposite edges of said plate that are extended beyond the concave face thereof, and a reenforcing panel extended from end to end on the concave face of said plate spaced inwardly from said flanges whereby channels are defined on the concave face of said plate intermediate said panel and said flanges, the free edges of said flanges, the face of said panel and the concave face of said plate transversely thereacross being disposed in different and spaced apart planes to thereby effectively reenforce said plate, the free edges of said flanges being disposed in a plane spaced from the concave face of the plate in an amount greater than is the plane in which the face of said panel is disposed, whereby said flanges serve to retain the body of a brake shoe or the like in which the reenforce plate is incorporated against separation in the event of fracture of said body.

15. A substantially rectangular reenforce plate for a brake shoe or the like embodying a concavo-convex configuration longitudinally thereof, flanges along the side edges of said plate extended beyond the concave face thereof, and a reenforcing panel on the concave face of said plate spaced inwardly from said flanges whereby channels are defined on the concave face of said plate intermediate said panel and said flanges, said plate having substantially T-shaped openings formed therein substantially midway between the ends thereof and respectively aligned with said channels and having stem portions thereof extended toward each other.

ROBERT B. POGUE.
